(57) **CLAIM**

The ornamental design for a mop, as shown and described.

DESCRIPTION

FIG. 1 is a perspective view of a mop in accordance with the present invention;

FIG. 2 is a side view of the mop seen in FIG. 1; the opposite side view being a mirror image thereof;

FIG. 3 is a front view of the mop.

FIG. 4 is another perspective view of the mop as seen in FIG. 1, with the unclaimed portions shown in FIG. 1 removed to show the underlying detail;

FIG. 5 is another view of the mop seen in FIG. 2, with the unclaimed portions shown in FIG. 2 removed to show the underlying detail; and

FIG. 6 is another view of the mop as seen in FIG. 3, with the unclaimed portions shown in FIG. 3 removed to show the underlying detail.

The broken lines are for environmental purposes, and do not form part of the claimed design.
